ATTORNEY

UNITED STATES PATENT OFFICE

EARL W. STORMS, OF HUNTINGTON PARK, CALIFORNIA

RADIATOR CLOSING MEANS FOR AUTOMOBILES

Application filed March 21, 1930. Serial No. 437,793.

My invention relates to improvements in radiator service closing means for automobiles by the use of which the radiator is closed and opened automatically by the cover 5 on the hood. The primary object is to abolish the use of an independent cap for the radiator thus simplifying and reducing cost of construction and facilitating the act of replenishing water or other liquid in the radiator. A further advantage is attained by avoiding all possibility of loss of the cap.

In the accompanying drawings forming part of this specification, Fig. 1 is a fragmentary view of the hood and radiator of an automobile shown equipped with my improved closing means, the cover of the hood being shown partly raised; Fig. 2 is a section taken on line 2—2 of Fig. 1, showing a portion of the hood cover and the cap of 20 my improved radiator closing means; Fig. 3 is a section taken on line 3—3 of Fig. 1; Fig. 4 is a front elevation of a fragment of an automobile hood and radiator, a portion being broken away and showing an alternative 25 construction of my invention, and Fig. 5 is a side elevation of a portion of the neck of the radiator and cap illustrated in Fig. 4 and showing the stopper opened by its spring.

In the drawings A indicates one of the sections of the hinged cover of the hood B of an automobile and C the usual radiator by the use of which water or other suitable cooling liquid is circulated through the walls of the cylinders of the motor. In applying my 35 invention the radiator is provided with a service opening under the hood immediately below the cover section A and may have a neck 10 at the outer end of which is a cap or stopper seat 11. Said cover section is provided 40 with a stopper or cap D which is secured thereto by a cleat 12, said cleat being fastened to the cover section by rivets 13 or other suitable means and adapted to close and seal the opening entering the radiator automatically when the cover section of the 45 hood is closed. Likewise when the cover section of the hood is opened, the closing cap of the radiator is raised into superior position so that cooling liquid can be replenished 50 in the radiator. The cap D is shown provided

with a resilient stopper 14 made of rubber or other suitable material which assists in closing the radiator tightly. When desired the cap 15 (see Fig. 5) can be mounted on the neck 16 of the radiator by the use of a spring hinge 17 as shown, said hinge causing the cap to open automatically when the cover section of the hood is closed. The cap is arranged so that the cover in closing will strike the cap and turn it down against the tension of the spring hinge and hold it closed over the neck of the radiator. The cap 15 is also provided with a leaf spring 18 against which the cover of the hood presses when closing to provide for any unevenness so that inequalities are compensated and the cap will always be closed tightly by the hood cover. This spring tension is also embodied in the cap by a resilient stopper element 19.

It will be understood that the hood cover is of usual type and that it is adapted to be closed, the usual locking means 20 functioning to hold the hood cover and radiator cap closed simultaneously both in the preferred and alternative construction described.

In accordance with the patent statutes, I have described the principles of operation of my invention together with the construction thereof which I now consider to represent the best embodiment thereof, but I desire to have it understood that the construction shown is only illustrative and that the invention can be carried out by other means and applied to uses other than those above set forth within the scope of the following 85 claims.

Having described my invention, what I claim as new and desire to secure by Letters Patent is:

1. In combination with the hood and radiator of an automobile, said hood having a hinged cover element and said radiator having a service inlet within said hood and below said cover, a cap element arranged to close and seal said inlet and movable to open said inlet, said cap element co-operating with said cover element and influenced thereby to cause said inlet to be closed and sealed when the cover element is closed and to be opened 100

automatically when the cover element is opened.

2. In combination with the hood and radiator of an automobile, said hood having a hinged cover element and means for holding the cover element closed and said radiator having a service inlet within said hood and below said cover element when the latter is closed, a cap element carried by said cover element and movable therewith, said cap element being arranged to close and seal said inlet and to be held closed and sealed when the cover element is closed and to open said inlet when the cover element is raised.
  3. In combination with the hood and radiator of an automobile, said hood having a hinged cover element and said radiator having a service inlet within said hood and below said cover element when the latter is closed, a cap element movably supported over said inlet and arranged to close over said inlet automatically through the closing movement of said cover element and to open automatically through the opening of said cover element.
  4. In combination with the hood and radiator of an automobile, said hood having a hinged cover element and said radiator having a service inlet within said hood and below said cover element when the latter is closed, a cap element movably supported over said inlet and arranged to close and seal said inlet automatically through the closing movement of said cover element and to open automatically through the opening of said cover element, and resilient means embodied between said cap and cover elements whereby inequalities are compensated and the cap may be held closed under tension.
- 40 In witness whereof, I have signed my name to this specification.

EARL W. STORMS.
